UNITED STATES PATENT OFFICE.

JOHN B. ROMANS, OF HELENA, ARKANSAS, ASSIGNOR OF ONE-HALF TO
CHARLES R. COOLIDGE, OF SAME PLACE.

BALING-PRESS.

SPECIFICATION forming part of Letters Patent No. 352,572, dated November 16, 1886.

Application filed June 26, 1886. Serial No. 206,358. (No model.)

To all whom it may concern:

Be it known that I, JOHN B. ROMANS, a citizen of the United States, residing at Helena, in the county of Phillips and State of Arkansas, have invented a new and useful Improvement in Baling-Presses, of which the following is a specification.

My invention relates to an improvement in baling-presses; and it consists in the peculiar construction and combination of devices that will be more fully set forth hereinafter, and particularly pointed out in the claims.

In the drawings, Figure 1 is a side elevation, partly in section, of a baling-press embodying my improvements, showing the parts in position before toggle-levers are operated. Fig. 2 is a vertical transverse sectional view of the same. Fig. 3 is a view similar to Fig. 1 after toggle-levers are operated.

A represents the ground frame comprising the sills B, the ends of which are connected by the cross-beams C. From the upper side of the ground sills, near the centers thereof, project four vertical posts, D, forming a rectangular vertical guiding-frame. The upper ends of the posts D are connected together by the bars E and the transverse bars F. The inner corners of the posts D are provided with rectangular vertical grooves G.

H represents vertical standards, which project from the upper side of the sills B, and are connected together in pairs at each end of the vertical guiding-frame by cross-beams I, on which are secured bearing-blocks K, the said bearing-blocks being located in a line with the longitudinal center of the frame A.

L represents a vertical rectangular press-box, which is provided at its upper end with the folding doors M. On the sides of the press-box, near the upper end thereof, are the hinged outwardly-folding doors N, and on the ends of the press-box, and also near the upper end thereof, are the hinged outwardly-folding doors O. The bottom of the press-box is open. The sides and ends of the press-box are secured between rectangular inclosing-frames P, which are located at the upper and inner ends of the press-box, and the corners of the said frames fit in the grooves G in the inner corners of the vertical guiding-frame,

thus adapting the press-box to be moved vertically in the said frame.

R represents vertical iron rods, which pass through the corners of the frames P, and are secured thereto by clamping-nuts S, which work on screw-threads made on the said rods. The lower ends of the rods R depend from the lower end of the press box, and to the lower ends of the said rods is attached a platen-board, T, by means of nuts U, which are screwed onto the lower ends of the rods.

V represents a longitudinal horizontal shaft, which is journaled in the bearing-boxes K and extends centrally through the lower side of the vertical guiding-frame under the press-box. One end of the shaft V is provided with the right-hand screw-threads V', and the other end of the said shaft is provided with the left-hand screw-threads V², the said right and left hand threads extending very nearly to the center of the shaft. To one end of the shaft is attached a crank-arm, W, by means of which the shaft may be rotated. If the press is to be operated by steam or horse power or other suitable motor, the crank W will be removed and a suitable driving-pulley attached to the end of the shaft V instead.

X represents sliding blocks, which are provided with screw-threaded openings that work upon the right and left hand screws of the shaft V. A bracket, T', projects vertically from the center of the platen T, and toggle-jointed arms Y have their outer ends pivoted to the lower ends of the blocks X, the inner ends of the said toggle-jointed arms being pivoted to the bracket T'.

Z represents the follower, which is adapted to move vertically in the press box from the under side of the same. From the lower side of the said follower, at the center thereof, depends a bracket, Z'.

A' represents a pair of toggle-jointed arms, the outer ends of which are pivoted to the upper ends of the sliding blocks X, and the inner jointed ends of the said toggle-arms are pivoted to the depending bracket Z'.

The operation of my invention is as follows: When the shaft V is turned in one direction, the blocks X are caused to recede from each other, and thereby straighten the toggle-arms 100

A' and Y and cause them to lower the follower Z and raise the platen T. As the press-box is connected to the platen, it will be understood that the press box is caused to partake of the motion of the platen, and thus it will be seen that as the follower is lowered the press-box is raised, the said follower and press-box thus moving simultaneously in opposite directions. In order to form a bale of cotton or other material the follower is caused to enter the lower open side of the press-box, so as to form the bottom for the same, and the doors M, N, and O, at the upper end of the press-box, are opened and a suitable quantity of cotton or other material to form a bale is thrown into the press-box, when the said doors are closed. The shaft V is then turned so as to cause the follower to be raised in the press-box and the latter to be lowered on the follower, thereby compressing the cotton or other material in the upper end of the press-box and forming a bale thereof. As the follower and the press-box both move simultaneously in opposite directions, it will be understood that the operation of forming a bale is very quickly performed.

A baling-press thus constructed is cheap and simple, is very strong and durable, is easily operated, and is not likely to get out of order. It will be noted that only a tensile strain is exerted upon the toggle-jointed arms and the rods R, thus permitting the said arms and rods to be made comparatively slender and light without affecting the strength and durability

of the press, thus enabling the latter to be constructed very cheaply and so light in weight as to enable it to be readily transported from one place to another.

Having thus described my invention I claim—

1. The press-box P, having the folding doors M at its upper side to form the top of the box, the side doors, N, to form the front and rear sides of the upper portion of the press-box, and the doors O at the upper sides of the ends 45 of the press-box, for the purpose set forth, the lower end of the press being open to receive the follower, substantially as described.

2. The combination of the guiding-frame, the press-box and platen movable in the said frame, the said press-box being rigidly connected to the said platen and having the doors M, forming one end, the other end being open, the follower in the open end of the press-box, the right and left hand screw-threaded shaft, the blocks fitting on the said shaft, and the toggle-jointed levers connecting the said blocks to the follower and platen, whereby the press-box and the follower will be moved simultaneously in opposite directions when the screw-shaft is 60 turned, substantially as described.

In testimony that I claim the foregoing as my own, I have hereto affixed my signature in presence of two witnesses.

JOHN B. ROMANS.
